1,981,975

COIN SLOT PURSE

Edward Weimar, Hoboken, N. J., assignor of one-half to George Naughton, Bronxville, N. Y.

Application April 19, 1933, Serial No. 666,823
Renewed August 10, 1934

1 Claim. (Cl. 150—37)

One object of this invention is the provision of a coin-holding slot on purses, hand bags, and the like, in which a number of coins such as nickels may be carried on the outside of the bag ready 5 to be emitted at the moment the coin is required, thus eliminating the necessity of opening the purse and searching therein for the coin.

Another object of the invention is the provision 10 of such a coin holder secured to the side of a bag and provided with means for quickly discharging a coin therefrom.

The above and other objects will become apparent in the description below, in which characters of reference refer to like-named parts in 15 the drawing.

Referring briefly to the drawing, Figure 1 is a perspective view of a purse equipped with the coin holder.

Figure 2 is an enlarged side elevational view of 20 a fragment of the purse, showing the coin holder.

Figure 3 is a cross-sectional view taken on the line 3—3 of Figure 2.

Figure 4 is a cross-sectional view taken on the line 4—4 of Figure 2.

Figure 5 is a cross-sectional view taken on the line 5—5 of Figure 2.

Referring in detail to the drawing, the numeral 10 represents a purse having the side wall 11. Such bag walls are usually formed of two layers 30 of leather 12 and 13. The outer layer 12 is cut out to provide a vertical slot. A housing 14 of rigid material such as a metal, rectangular in cross-section, is mounted between the layers 12 and 13. The front wall 15 of the housing 14 is 35 provided with a slot 16, and each side of the wall surrounding the slot is provided with an extension 17 which is doubled back against the wall with the leather of the layer 12, that is, the edges of the latter which bound the vertical slot in the 40 leather, clamped therebetween, thus locking the housing 14 to the bag.

The housing 14 is further provided with a floor 18, and the front wall 15 thereof is provided with upper extremities which are doubled over to form 45 edge reinforcements 19 at the top or mouth of the housing. Slidably mounted within the housing 14 is a lug 20 of the same conformation as the housing and substantially bridging the gap 50 between the opposite end walls 22 thereof. This lug is provided with a grip tongue or handle 21 which projects through the slot 16.

Near the upper end of the housing, the end walls 22 are cut out at 23, and the bases of spring 55 fingers are secured to said walls at 24 at the edge

of the cut-out, the arcuate free ends 25 of these fingers extending into the housing through these cut-outs and having their convex sides mutually-opposed.

In use, the lug 20 lies at the bottom of the housing 14, and a number of coins are forced through the mouth past the springs 25, taking the positions shown dotted in Figure 2. When a coin is desired, the lug 20 is raised by handle 21 until the uppermost coin has been forced past the 35 springs 25. This operation is of the simplest. The springs 25 normally prevent the coins from leaving the housing in case the bag is upset or shaken.

Obviously modifications in form and structure 70 may be made without departing from the spirit and scope of the invention.

I claim:

In combination with a hand bag or the like, a housing adapted to be secured to the bag comprising four walls enclosing a compartment substantially rectangular in cross-section, one of said walls having a longitudinal slot therein, each side of said slotted wall having an extension adjacent the slot, said extensions being doubled back 75 against said slotted wall with the material forming the bag clamped therebetween to lock the housing to the bag, a lug slidably mounted in said housing and having a tongue extending through the slot in said slotted wall, and resilient 80 means near the top of said housing for releasably retaining a plurality of coins therein.

EDWARD WEIMAR.
